UNITED STATES PATENT OFFICE

2,513,822

CUTOUT CONSTRUCTION

William O. Schultz, South Milwaukee, Wis., assignor to McGraw Electric Company, a corporation of Delaware

Application April 28, 1947, Serial No. 744,472

5 Claims. (Cl. 200—114)

1

This invention relates to a cutout construction. This invention is an improvement over that disclosed in my United States Patent No. 2,372,126 of March 20, 1945, for Drop-Out Fuse Device.

In general, this invention has the same objects as those set forth in my above noted patent.

Further objects are to provide a cutout construction of a drop-out type in which the upper stationary contact is a rigid member of simple construction, in which the lower stationary contact consists of a heavy U-shaped member making only line contact with the contact carried by the door, and in which resiliency is provided between the upper, rigid stationary contact and the upper contact of the cutout by means of a floating spring pressed lever.

More specifically, further objects are to provide a housed type of drop-out fuse cutout in which the upper stationary contact of the housing is rigid and in which a rigid lower contact is carried by the door and engages and is held by the lower stationary contact, and in which a floating spring pressed throw-out lever is provided which not only acts as a throw-out lever for extracting any remaining portion of the fuse link upon rupture thereof, but also acts in the dual capacity of providing heavy substantially line contact with the lower contact of the door, and also which provides, together with the auxiliary lever, a yielding heavy pressure between the upper contact of the fuse tube and the upper stationary contact, the construction being such that after rupture of the fuse link the throw-out lever detaches itself from the lower contact of the door and moves downwardly with the fuse tube and is electrically dead in its final position so that there are no live projecting parts extending outwardly from the bottom of the housing.

An embodiment of the invention is shown in the accompanying drawings, in which:

Figure 1 is a side elevation partly broken away and partly in section showing the fuse in its uppermost or operative position.

Figure 2 is a bottom view of the structure shown in Figure 1.

Figure 3 is a top view of the device with parts broken away and parts in section.

Figure 4 is a sectional view on the line 4—4 of Figure 1, such view being approximately a line section.

Figure 5 is a sectional view approximately on the line 5—5 of Figure 1.

2

Figure 6 is a sectional view approximately on the line 6—6 of Figure 1.

Figure 7 is a fragmentary sectional view partly broken away of the lower portion of the cutout.

Figure 8 is a view showing an intermediate position of the lower mechanism immediately after rupture of the fuse link.

Figure 9 shows the final inoperative or circuit-open position.

Referring to the drawings, it will be seen that the cutout comprises a housing 1 of insulating material and a door 2 also of insulating material and preferably supported from the housing by means of trunnions 3 carried by the lower contact 4 of the door 2 and removably seated within hook-like spaced portions 5 carried by the housing.

The lower stationary contact or terminal of the housing consists of a heavy yielding U-shaped spring member 6 which is adapted to securely engage ribs 7 formed on the lower contact 4 carried by the door and to have therewith substantially line contact as shown in Figures 4 and 6.

The upper stationary contact or terminal is a rigid U-shaped member 8 carried by the housing and provided with conical recessed portions 9 in the lower edges of the arms of this U-shaped member 8. The upper and lower terminals are each provided with a rigid transverse bar 10 which is grooved on its rear side and is adapted to be respectively engaged by the line and load conductors 11 and 12, suitable clamping means 13 being provided. It is also preferable to provide a barrier 14 formed integrally with the housing 1 and located between the upper and lower stationary terminals.

The fuse tube is formed of insulating material and is indicated by the reference character 14. It is provided with an upper terminal 15 which has outwardly projecting rigid, conical ears or members 16 which fit within the conical recesses 9 of the rigid upper stationary contact 8. It is provided with the usual screw cap 17 for locking the button on the fuse link in place as shown in my above noted patent. The upper terminal of the fuse tube is provided with a pair of laterally projecting arms 18, see Figure 3, which ride against ribs or portions 19 formed integrally with the door. Further the upper terminal 15 of the fuse tube is provided with an outwardly projecting tongue 20 which is positioned between the ribs 19 but which has plenty of lateral play as may be seen from Figure 3, so as to leave the upper terminal of the fuse tube

free to adjust itself accurately to the conical recesses 9 formed in the upper stationary terminal 8 of the housing. The ribs 19 extend downwardly but approach each other to provide a relatively narrower slot 21 therebetween for guiding the tongue 20 downwardly centrally of the door when the fuse tube drops downwardly to its inoperative position.

The lower terminal 4 of the door loosely guides the fuse tube 14 and allows it to slide downwardly from the position shown in Figure 1 to its final position shown in Figure 9 upon rupture of the fuse link, such fuse link being indicated generally by the reference character 22. The lower contact 4 of the door is provided with a box-like lower portion indicated by the reference character 4'. This box-like portion 4' is provided with a rear slanting wall 23 which is formed of a pair of inwardly shaped fingers formed integrally with the lower contact of the door.

The fuse tube is provided with a collar 24 adjacent its open lower end and this collar is equipped with a pair of spaced ears 25 between which an auxiliary lever 26 is pivoted. This auxiliary lever is spring pressed in a counter-clockwise direction by means of the spring 27 and is provided with a pair of forwardly projecting fingers 28 which engage the collar 24 when the fuse link blows and the auxiliary lever moves to the position shown in Figures 8 and 9. The auxiliary lever carries a floating lever or throw-out lever 29 adjacent its inner end. The floating lever or throw-out lever 29 is provided with a threaded stud 30 and a thumb nut 31 for clamping the leader of the fuse link 22 in place.

It is to be noted from reference to Figure 7 that the throw-out lever or floating lever 29 is provided with a rearwardly projecting ear 32 which engages the slanting wall 23 of the lower contact 4 of the door with a heavy pressure and has substantially line contact therewith.

It is to be noted that when the leader of the fuse link 22 is clamped to the throw-out lever 29 and the parts are in the position shown in Figure 7, that the arm or ear 32 of the throw-out lever acts as a fulcrum against the wall 23 and holds the intermediate or auxiliary lever 26 in its stressed position shown in Figure 7. This urges the conical ears 16 of the upper terminal 15 of the fuse tube against the rigid stationary terminal 8 and provides heavy contact pressure at that point, it being noted that heavy contact pressure is obtained between the arm 32 of the throw-out lever and the wall 23 of the lower terminal 4 of the door. To express this in other words, it is apparent from an examination of Figure 7 that the left-hand end of the lever 26 is thrust downwardly by means of the spring 27 and tends to force the lever 29 downwardly. The right-hand end of the lever 29 is prevented from downward motion by being secured to the fuse link. The left-hand end or portion 32 of the lever 29 therefore tends to move downwardly and presses downwardly against the portion 23 of the terminal 4 carried by the door. Consequently, there is an upward thrust imparted to the fuse tube 14 which tends to force the fuse tube 14 upwardly and thereby forces its upper contacts or conical ears 16 against the upper stationary terminal 8 carried by the housing. Heavy contact pressure is also obtained between the stationary lower terminal 6 of the housing and the lower terminal 4 of the door. The current is transferred directly from the fuse link to the throw-out lever and

through the heavy line contact between the arm 32 and the wall 23 to the lower terminal 4 of the door.

Upon rupture of the fuse link, the throw-out lever or fuse link extracting lever 29 rocks in a clockwise direction, being urged towards this motion by means of the spring pressed auxiliary lever 26. The throw-out lever 29 is a floating lever and its fulcrum or arm 32 rocks and slides along the slanting walls 23 of the lower terminal 4 of the door and finally passes from the wall 23 and allows the fuse tube to drop downwardly to its inoperative position shown in Figure 9. It is to be noted that when the parts are in this final position, that all projecting parts carried by the fuse tube are electrically dead and, therefore, there is no resulting hazard as would have been the case had the parts been live.

It will be seen that a novel form of cutout construction has been provided wherein heavy contact pressure is obtained between the rigid stationary contact of the housing and the rigid contact or upper terminal of the fuse tube and wherein substantially line contact has been obtained between the lower stationary terminal and the terminal carried by the door, and in which a system of levers is provided whereby a floating throw-out lever not only extracts any remaining portion of the fuse link upon rupture thereof and also furnishes the upward thrust on the fuse tube to secure the heavy contact pressure between the upper terminal of the fuse tube and the upper stationary terminal, the lever construction being such that all parts projecting from the housing following rupture of the fuse link are electrically dead in the final inoperative position of the fuse tube.

It is to be noted that the auxiliary lever and the throw-out lever are both normally housed within the sleeve and are thus quite well protected against striking any of the parts of the housing when the door is being replaced.

Although this invention has been described in considerable detail, it is to be understood that such description is intended as illustrative rather than limiting, as the invention may be variously embodied and is to be interpreted as claimed.

I claim:

1. A drop-out cutout comprising a rigid upper stationary terminal and a lower stationary terminal, a movable tubular member of insulating material having an upper rigid terminal normally engaging said upper stationary terminal, circuit interrupting means within said tubular member connected to the upper terminal of said tubular member, stationary means, and mechanism including a downwardly spring pressed floating lever supported from the lower portion of said tubular member and normally restrained from motion by said circuit interrupting means and engaging said stationary means to restrain said tubular member from motion and arranged to release said tubular member when said circuit interrupting means functions, said mechanism being arranged to yieldingly hold the terminal of said tubular member in engagement with said rigid upper stationary terminal.

2. A drop-out fuse construction comprising a rigid upper stationary terminal, a lower stationary terminal, a fuse tube having a fuse link therein and having an upper terminal connected thereto and normally engaging said rigid upper stationary terminal, a sleeve for guiding said fuse tube, said sleeve being normally connected to said lower stationary terminal, and a floating, down-

wardly spring pressed lever supported from said fuse tube and housed within said sleeve and having one end connected to said fuse link and having the other end supported from the interior of said sleeve, said floating lever being arranged to urge the terminal of said fuse tube into engagement with said rigid upper stationary terminal.

3. A housed type drop-out fuse construction comprising a housing, a door for said housing, said door having a sleeve constituting a lower terminal, a lower stationary terminal having a pair of spring arms arranged to engage the lower terminal of said door and having a line contact therewith, an upper stationary terminal, a fuse tube slidably carried by said sleeve and having an upper terminal normally engaging said upper stationary terminal with a direct upward thrust, and spring biased throw-out means restrained by said fuse link and arranged to impart an upward thrust to said fuse tube and to electrically connect with said sleeve and being normally housed within said sleeve.

4. A housed type drop-out fuse construction comprising a housing, a door for said housing, said door having a sleeve constituting a lower terminal, a lower stationary terminal having a pair of spring arms arranged to engage the lower terminal of said door and having a line contact therewith, an upper stationary terminal, a fuse tube slidably carried by said sleeve and having an upper terminal normally engaging said upper stationary terminal with a direct upward thrust, and spring biased throw-out means restrained by said fuse link and arranged to impart an upward thrust to said fuse tube and to electrically connect with said sleeve and having a line contact therewith and arranged to release said fuse tube for downward sliding motion and detach itself from said sleeve on rupture of said fuse link.

5. A drop-out fuse construction comprising upper and lower stationary terminals, a fuse tube having an upper terminal normally interlocking with the upper stationary terminal and detachable therefrom, a fuse link extending downwardly from the upper terminal of said fuse tube and projecting outwardly through the lower end thereof, a sleeve-like member slidably supporting said fuse tube and normally engaging said lower stationary terminal, a spring pressed lever pivotally supported from the lower portion of said fuse tube and having a free end biased downwardly, a throw-out lever pivoted intermediate its ends on the free end of said spring pressed lever and having one end detachably interlocking with said sleeve-like member and having pressure contact therewith and having the fuse link extending over the other end thereof, said throw-out lever constituting a floating lever and coacting with said spring pressed lever to allow said fuse tube to slide downwardly a slight distance when said fuse tube is moved into operative position, said spring pressed lever and said throw-out lever being arranged to transmit upward thrust to said fuse tube to thereby hold the upper terminal of said fuse tube in pressure and interlocking contact with said upper stationary terminal.
